Inventor;

Otis H. Weed

United States Patent Office.

OTIS H. WEED, OF BOSTON, MASSACHUSETTS.

Letters Patent No. 98,823, dated January 11, 1870.

IMPROVED WASHING-MACHINE.

The Schedule referred to in these Letters Patent and making part of the same.

To all it may concern:

Be it known that I, OTIS H. WEED, of the city of Boston, and State of Massachusetts, have invented a new and improved Washing-Machine and ironing-table combined, of which the following is a clear, exact, and full description, reference being had to the accompanying drawings, in which—

Figure I is a perspective view of my new machine, closed up and adapted for table-purposes.

Figure II is a vertical sectional view of the same, through the lines $x-x$.

Figure III is a plan or top view with the cover removed.

Figure IV is a vertical section through the lines $y-y$, showing the corrugated washers.

Figure V is the wash-board removed from its position in the machine.

The object of my invention is to provide a cheap and reliable, but at the same time a convenient machine for washing clothes, which will allow the person operating it to be seated, and one which, when not in use, can be used as a kitchen or ironing-table.

To enable others skilled in the art to understand and use my invention, I will proceed to describe the manner in which I have carried it out.

In the said drawings—

A represents the box or outer casing of my machine. It is evident that while this casing may be manufactured out of very cheap material, and at a very low price, it may also be made of fine material, so as to constitute a handsome piece of furniture.

B is the top of my machine, which fits tightly upon the box A, so as to prevent the escape of water during the process of washing.

This top also forms the kitchen or ironing-table when the machine is not being used for washing.

a a are legs supporting the washing-machine and table.

C is a corrugated and perforated wash-board, placed in one end of the box A, to catch the pressure of the clothes when the machine is in operation. Instead of this board, a series of bars might be used.

In the rear of the board C, and between it and the end of the box A, are placed the springs c c, so as to secure an easy yielding motion to the wash-board, which will cause the board to adjust itself to the pressure of the washers D D. These washers move in parallel lines, and alternately toward the wash-board C, being held in place by means of the guides b b and grooves d d, and being worked by the bent shaft E, to which the washers are attached by the connecting-rods e e, which may be made either rigid or with springs.

The bent shaft E has its bearings in the sides of the box A. It passes into the bearing at m, through the slot n, which slot is subsequently covered by the plate s, secured to the box A by means of the screws r r.

F is an outlet, through which to discharge the water.

When the machine is used as a table, the crank G is slipped off and stored inside of the machine.

Claim.

What I claim as my invention, and desire to secure by Letters Patent, is—

The washing-machine and table combined, consisting of the box A, the top B, the wash-board C, with its springs c c, the washers D D, the springs g g, guides b b, the connecting-rods e e, and bent shaft E, all constructed, combined, and arranged as shown and described.

OTIS H. WEED.
